ASH TRAY

Frank R. Barto, Junction City, Oreg.

Application September 27, 1949, Serial No. 5,182

Term of patent 14 years

(Cl. D85—2)

To all whom it may concern:

Be it known that I, Frank R. Barto, a citizen of the United States, residing at Junction City, in the county of Lane and State of Oregon, have invented a new, original, and ornamental Design for Ash Trays, of which the following is a specification, reference being had to the accompanying drawing, forming part thereof.

Figure 1 is a perspective view of an ash tray, showing my new design.

Figure 2 is a side elevational view thereof, taken from the upper left of Figure 1.

Figure 3 is a top plan view thereof.

I claim:

The ornamental design for an ash tray, as shown.

FRANK R. BARTO.
